UNITED STATES PATENT OFFICE.

JOHN A. WEBER, OF TOLEDO, OHIO.

POWER LOG-LOADER.

1,099,221.

Specification of Letters Patent.

Patented June 9, 1914.

Application filed August 19, 1912. Serial No. 715,774.

To all whom it may concern:

Be it known that I, JOHN A. WEBER, a citizen of the United States, and a resident of Toledo, in the county of Lucas and State of Ohio, have invented a certain new and useful Power Log-Loader; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to saw-mill apparatus, and particularly to means for controlling the movements of logs down skidways, and also for assisting in turning a log upon its sawed side after a cant has been cut therefrom.

The object of my invention is to facilitate the handling of logs and cants in sawmills by the provision of a rocker log feeding means, which may be operated to effect a feeding of logs down the skidway, or may be placed in inoperative position so as to enable cants to be moved back upon the skidway preparatory to being further sawed.

A further object of my invention is the provision of a manually controlled means for assisting in turning a log, after being sawed, with its sawed face down on the carriage, whereby to materially lessen the labor incident to log handling in saw-mills.

The invention is fully described in the following specification and while, in its broader aspect, it is capable of embodiment in numerous forms, a preferred embodiment thereof is illustrated in the accompanying drawings, in which,

Figure 1 is a side elevation of the apparatus embodying my invention with parts broken away, and Fig. 2 is a top plan view thereof.

Referring to the drawings, 1 designates the carriage on which a log 2 is mounted when being sawed, and 3 the beams or timbers of the customary skidway down which the logs are rolled to the carriage. The skidway timbers 3 are shown as being arranged in pairs at each side thereof, with the timbers of each pair slightly spaced apart to permit the mounting of rocker-levers or log-feeding members 4 therebetween. The levers 4 are mounted on pivot-

pins 5 adjacent to the top edges of the timbers 3 and are attached at their forward ends to eccentric strap-arms 6, the straps of which are mounted on eccentrics 7 carried by a shaft 8, which shaft extends transversely of the skidway beneath the timbers thereof and is journaled in bearing-brackets 9 depending from the under side of said timbers. The strokes of the eccentrics 7 are such that when the forward ends of the rocker-levers 4 are at the limit of their upward movements they stand in log obstructing positions, as shown in Fig. 1, and when at the limit of their downward movements the forward ends of such levers stand below the upper edges of the skidway timbers, as indicated by dotted lines in Fig. 1. A removable heel-piece 10 is mounted on the top side of the rear end of each lever 4 and serves to coact with a log to roll it forward on the skidway when the rear end of the lever is raised from lowered position, as is apparent. The levers 4 are so shaped that when the heel-pieces 10 are removed therefrom and the forward ends of the levers are in lowered position the rear ends of the levers will stand below the top surface of the skidway timbers, thus preventing any obstructions on the top surface of the skidway to the back sliding of cants thereon, which is quite an important feature in sawmill operation.

The shaft 8 is shown as carrying a sprocket-wheel 11 which has connection through a sprocket-chain 12 with a sprocket-wheel 13 on a drive-shaft 14, which is mounted in the skidway frame work and is driven in any suitable manner. A friction-clutch 15 is mounted on the shaft 14, and its movable member is connected to a control lever 16 through a lever 17 and connecting-rod 18.

A single revolution clutch 19 of any suitable construction is fixed to the shaft 8, and, in the present instance, has a clutch-pin 20 which is adapted to engage the sprocket-wheel 11 and communicate rotation to the shaft when the trip-pin 21 is retracted. When the shaft has completed a revolution the trip-pin coacts with a part of the clutch-pin to retract it from sprocket-wheel engaging position, as is well understood in the art. The tripping of the trip-pin 21 is controlled from a foot-treadle 22, which has connection therewith.

Mounted on pivots 23 adjacent to the for-

ward ends of the skidway timbers are a set of blocks 24, which have their forward ends vertically broadened and of convexed circular form and are provided at their rear ends 5 with tail-pieces 25 to which control cables 26 are attached. The cables 26 pass from the tail-pieces 25 around sheaves 27, which are disposed below and in advance thereof, and then extend rearward and attach to rocker- 10 arms 28 projecting upward from a rock- shaft 29 that is mounted in the skidway framework transversely thereof. The blocks 24 normally stand in lowered or inoperative positions relative to the skidway by reason 15 of the gravity action thereof, and are raised to the operative position shown in Fig. 1 by a depression of a foot-treadle 30 on the shaft 29, which effects a rocking of said shaft and a consequent pulling of the cables 26 to 20 lower the tail-pieces 25 and raise the blocks 24, as is apparent. When the blocks 24 are raised to operative position their curved sides extend upward and rearward from adjacent to the edge of the carriage 1, so that 25 when a partially sawed log 2 is tipped over with its sawed side against the curved edges of the blocks 24 the log will tend to have a rolling and downward and forward sliding movement on the blocks, due to the center of 30 gravity of the log being above its point of first contact with the blocks, thus effecting a consequent forward movement of the lower sawed edge of the log so that the log will then slide by gravity to flat position on the 35 carriage, or in position to have another cut taken therefrom at right-angles to the first or previous cut. It is found in practice that the provision of the blocks 24 materially facilitates the turning of logs on the carriage 40 for the purpose of taking successive cuts of the same at right angles to each other, and greatly lessens the labor which has heretofore been incident to such turning.

In the use of my improved log turning attachment, the operator, in feeding a log 45 down the skidway to the carriage depresses the treadle 22 to permit an engagement of the clutch-pin 20 and rotating sprocket-wheel 11, thus imparting a single revolution to the shaft 8 and eccentrics 7 and a consequent movement to the log feeding levers 4 to lower their forward ends from log obstructing position and raise their rear ends 50 to cause the heel-pieces 10 to coact with the under side of a registering log to force it forward down the skidway, after which the levers are returned to the normal at rest position shown. If it is desired to move cants 55 back upon the skidway as they are cut from a log, to render them accessible for a subsequent cutting into smaller pieces, the logs 60

are blocked to the rear of the feeding levers 4 and the heel-pieces 10 removed from the levers to permit such levers to be moved into inoperative position, as shown by dotted 65 lines in Fig. 1, thus enabling the cants to be slid back upon the skidway over said lever. When it is desired to turn a log on the carriage, after a cant has been cut from a side thereof, the operator depresses the foot 70 treadle 30 to effect a raising of the blocks 24 to the operative position shown in Fig. 1, and a helper on the carriage then cants the log over to cause its flat or sawed face to fall on the curved sides of said blocks. As the 75 sawed side of the log strikes the curved edges of the blocks below the center of gravity of the log, the log will roll partially around the curved block edges to effect a forward movement of the lower edge of the log, and the log will then slide by gravity into flat position upon the carriage.

It is apparent that both of the devices herein described materially facilitate the handling of logs and cants in saw-mill work 85 and also reduce the labor and expense incident to such work.

I wish it understood that my invention is not limited to any specific construction or arrangement of the parts except in so far as 90 such limitations are specified in the claims.

Having thus described my invention, what I claim as new, and desire to secure by Letters Patent, is,

1. The combination with a log skidway, of 95 a rocker-lever to obstruct the movements of a log down the skidway and then to feed an obstructed log forward, said lever having a part which is removable to enable the lever to wholly stand out of log obstructing position, and means for operating said lever.

2. The combination with a log skidway, of 100 a rocker-lever attached to said skidway, means attached to said lever and operable to move the forward end thereof upward 105 into log obstructing position, or vice versa, the rear end of said lever standing at all times below the top surface of the skidway, and a heel-piece removably carried by the rear end of the lever for coöoperating with 110 the lever to feed a superposed log forward when the rear end of the lever is elevated, and manually controlled means for imparting rocking movements to said lever.

In testimony whereof, I have hereunto 115 signed my name to this specification in the presence of two subscribing witnesses.

JOHN A. WEBER.
